CLAIM

The ornamental design for a furring channel, as shown and described.

DESCRIPTION

FIG. 1 is a backside perspective view of a furring channel showing an embodiment of the design;

FIG. 2 is a rear plan view of the furring channel of FIG. 1; FIG. 3 is a front plan view of the furring channel of FIG. 1; FIG. 4 is an end elevation view of the furring channel of FIG. 1;

FIG. 5 is an end elevation view of the furring channel of FIG. 1 opposite from the end shown in FIG. 4;

FIG. 6 is a side elevation view of the furring channel of FIG. 1; and,

FIG. 7 is a side elevation view of the furring channel of FIG. 1 opposite from the side shown in FIG. 6.

In the drawings, FIGS. 1-3, 6 and 7 show a symbolic break. Portions omitted between the break lines indicating indeterminate length form no part of the claimed design.

1 Claim, 6 Drawing Sheets
